UNITED STATES PATENT OFFICE.

HUGO V. STEUERNAGEL, OF HARTFORD, CONNECTICUT.

CLAMP.

Application filed May 7, 1924. Serial No. 711,622.

Fig. 1 is a face view of a "double-bar" clamp embodying one form which my invention may assume.

Fig. 2 is a view of the adjustable jaw 5 thereof in longitudinal section, with the tie-rods broken away.

Fig. 3 is a view in transverse section on the line 3—3 of Fig. 1.

Fig. 4 is a view corresponding to Fig. 2, 10 but showing separate plungers for operating the two clamping-dogs.

Fig. 5 is a face view of my invention as embodied in a "single-bar" clamp.

My invention relates to an improvement 15 in clamps of the type shown in United States Patent No. 1,126,116, granted to me January 26, 1915, the object being to produce a clamp constructed with particular reference to lightness, simplicity and fewness of parts, 20 compactness of form and ruggedness in use, and convenience and ease of operation.

With these ends in view, my invention consists in a clamp having certain details of construction and combinations of parts as 25 will be hereinafter described and particularly pointed out in the claims.

In carrying out my invention, as shown in Figs. 1 to 3 inclusive, the clamp comprises the usual parallel tie-rods 10, a cross-head 30 11 carrying a clamping-screw 12 having a slip-handle 13, a screw-actuated jaw 14 sliding on the said tie-rods 10, and an adjustable jaw 15 also sliding on the tie-rods 10 and chambered to receive two complementary 35 dogs 16 pivotally mounted upon pins 17 and having their outer ends serrated for engagement with the inner faces of the respective tie-rods 10, while their inner ends are formed with rounded coupling-lugs 18 entering 40 coupling-notches 19 formed in the opposite edges of a plunger 20 mounted in the block at a point midway the length thereof, between the said dogs and arranged with its axis parallel with the axes of the tie-rods 10 45 of the clamp. At its inner end, the plunger is formed with an axially-arranged stop in the form of a stem 21 encircled by a helical spring 22, which exerts a constant effort to move the plunger rearward and hence to 50 turn the jaws into position to grip the said tie-rods. The said stem 21 is adapted in length to engage with the inside of the jaw-face 23 of the block, so as to limit the movement of the plunger and prevent the undue 55 compression of the spring.

Under the construction described above,

both dogs are concurrently operated by direct endwise pressure upon a single plunger requiring no more space between the tie-rods for its operation than will permit the 60 introduction of a thumb or finger between them.

In the modified construction shown in Fig. 4, two plungers 24 are provided for the operation of the respective dogs, instead of one, 65 there being no other difference in the principle of construction and operation.

In the single-bar clamp embodying my invention, shown by Fig. 5 of the drawings, the tie-piece consists of a bar 25 mounting 70 a head 26 carrying a screw 27 having a slip-handle 28 and engaging with and operating a sliding-jaw 29 corresponding to the screw-actuated jaw 14 of the double-bar clamp already described. The tie-bar 25 also mounts 75 an adjustable block 30 sliding upon it, having a jaw-face 31 co-acting with the face 32 of the jaw 29 and mounting a dog 33 turning upon a pivot 34, having one end serrated to engage directly with the bar 25 and its 80 opposite end formed with a rounded coupling-lug 35 entering a coupling-notch 36 in a spring-actuated plunger 37 corresponding in construction and function to the plungers already described. 85

In the several embodiments of my invention herein shown and described, it is characterized by a dog pivotally mounted in a sliding block in position to grip a tie-piece or corresponding member of the clamp and 90 operated directly by a plunger also mounted in the block.

I claim:

1. In a clamp, the combination with a tie-member, of a block sliding thereupon and having a clamping-face, a dog pivotally mounted intermediate of its ends directly in the said block for bodily movement therewith, a plunger mounted in the said block, operatively connected with the said dog and 100 positioned to be manually operated by a blow for disengaging the dog from the tie-member, and a spring acting directly upon the said plunger for normally maintaining the said dog in engagement with the said 105 tie-member.

2. In a clamp, the combination with a tie-member, of a block sliding thereupon and having a clamping-face, a dog pivotally mounted intermediate of its ends directly in the said block for bodily movement therewith and provided with a cou-

- pling-lug, a plunger mounted in the said block for bodily movement therewith, formed with a notch for the reception of the coupling-lug of the dog and positioned to be manually operated by a blow for disengaging the dog from the tie-member, and a spring acting directly upon the said plunger for normally maintaining the said dog in engagement with the said tie-member.
- 10 3. In a clamp, the combination with two parallel tie-members, of a block sliding thereupon and having a clamping-face, two dogs pivotally mounted intermediate of its ends in the said block for bodily movement therewith and respectively adapted at their

outer ends to engage directly with the respective tie-rods and each provided upon its inner end with a coupling-lug, a plunger mounted in the said block between the said dogs, formed with notches for the reception of the coupling-lugs thereof and positioned to be manually operated by a blow for disengaging the dog from the tie-member, and a spring acting directly upon the said plunger for normally maintaining the said dogs in engagement with the said tie-members.

In testimony whereof, I have signed this specification.

HUGO V. STEUERNAGEL
